CARL D. BROWN, OF HOPEDALE, MASSACHUSETTS, ASSIGNOR TO DRAPER CORPORATION, OF HOPEDALE, MASSACHUSETTS, A CORPORATION OF MAINE.

PICKER MECHANISM FOR LOOMS.

Application filed November 18, 1927. Serial No. 234,114.

This invention relates to the picker mechanism of a loom.

It is very important, especially with certain classes of fabrics, that the shuttle shall be picked from its box accurately along a right line so that it shall not be deflected from the raceway either vertically or horizontally. If deflected even to a slight extent, the shuttle may be thrown against the shed with sufficient force to mark the fabric or even to damage or break the warps. In the weaving of silk or rayon fabrics, the damage caused to the fabric as the result of marks made by the shuttle in its travel through the shed must be considered.

It is the object of the present invention to provide a picker mechanism of such a character that it will not only have no tendency during the picking movement to deflect the shuttle from a true right line path, but that it will also act to insure the right line movement of the shuttle.

It is the object of the invention further to provide a picker mechanism of a character that will leave the side walls of the shuttle box intact so that they will have a perfect bearing engagement with the side walls of the shuttle.

It is the object of the invention further to provide a picker mechanism of a simple and efficient type of construction designed and capable of securing the desired results.

These and other objects and features of the invention will appear more fully from the accompanying description and drawings and will be particularly pointed out in the claims.

As the invention is capable of application to a wide variety of loom structures, and as such structures are well known and familiar to those skilled in the art, it will be sufficient to illustrate and describe a preferred form of the invention in connection with a single well known type of loom and to illustrate only those portions of the loom directly concerned with the invention.

Fig. 1 is a front elevation of the right-hand end of a portion of a loom with a preferred form of the invention embodied therein.

Fig. 2 is a view on a larger scale in transverse section taken on the line 2—2 of Fig. 1 with the shuttle shown in full.

Fig. 3 is a view in perspective of the picker and the upper end of the picker stick.

Fig. 4 is a view in horizontal cross section taken on the line 4—4 of Fig. 2.

Fig. 5 is a view in horizontal cross section taken on the axis of the picker guide rod with the guide rod shown in full.

The right-hand end of the loom is shown, but it will be understood that the construction, so far as the present invention is concerned, is, or may be, the same at the left-hand end.

The loom frame 1 carries at the lower end the lay rocker shaft 2, from which extend the lay swords 3 supporting in the usual manner the lay 4. The upper surface of the lay provides the raceway for the shuttle 5 herein shown in the form of a race plate 5 secured to the top of the lay and presenting a smooth surface upon which the shuttle travels.

At the end of the lay is the shuttle box 75 comprising the front and rear walls or binders 6 and 7 suitably faced at 8 and which may be mounted on the lay in any suitable or usual manner and comprising also the upper guiding wall 9 with its facing 10. 80 With this invention the front and rear walls 6 and 7 are left intact, so far as the picker mechanism is concerned, although, of course, a suitable aperture may be provided for a feeler mechanism. These walls, therefore, 85 fit snugly against the shuttle and afford a perfect bearing engagement with the shuttle, no long slot in either being required for the movement of the picker.

The picker is preferably a block of rawhide, or other suitable material, having a vertical web 11, a cylindrical head 12, and a cylindrical foot 13. The head 12 engages the point of the shuttle 14 at the end of its central axis. The web 11 of the picker rides in and is guided by a longitudinal slot 15 formed in the raceway or race plate 5 and extending longitudinally thereof, and parallel with the side walls of the shuttle. The foot 13 or lower end of the picker is guided on a rod 16 secured to the lay and extending longitudinally thereof beneath the slot 15 and parallel therewith. The mounting for the rod 16 is shown separately in Fig. 5. At the inner end a suitable bracket 17 on the lay is provided with a conical bore or seat 18 into which fits the conical end 19 of the rod 16. The outer end of the lay has a suitable bracket portion 20 provided with a cylindrical aperture 21 fitting the outer end 105 110

of the rod 16 and this aperture is threaded at its outer end to receive the threaded set screw 22. When the set screw 22 is screwed in, it will be seen that the rod 16 is forced firmly into the seat 18 and thus held accurately in position and a lock nut 23 on the set screw 22 insures the permanent position of the rod.

It will thus be seen that the picker is very accurately guided by the rod 16 at its lower end and the slot 15 at its upper end so that it can only move longitudinally of the lay with its shuttle engaging point moving on a right line parallel with the raceway and parallel with the side walls of the shuttle.

The picker is given this longitudinal movement by a construction which is so arranged as to have no tendency to deflect the picker from this right line movement and consequently no tendency to deflect the shuttle from its right line movement. This result is secured by mounting the picker stick entirely beneath the raceway, by having the upper end of the picker stick swing immediately adjacent to and parallel with the picker, by loosely connecting the picker stick to the picker and by using a construction of picker stick which has no vertical movement relatively to the picker.

The picker stick 24 illustrated is connected to a rocker shoe 25 of a familiar type which is so shaped that as it rocks on the surface of the rocker support 26, the upper end of the picker stick, where it engages the picker, will move in a horizontal path. The picker stick is shown as given its swinging movement in the plane of the lay and parallel with the path of the picker by the usual connection 27 extending to the usual pick motion. It will be noted that the picker stick 24 swings in a plane immediately adjacent to and parallel with the picker, as shown in Figs. 2 and 3. At its upper end, the picker stick is loosely connected to the picker so that it will not have any tendency to deflect the picker from its right line movement.

The connection between the picker stick and picker may, of course, be varied in form, but a simple and preferred connection for securing the desired results is illustrated. A lug 28 projects laterally from the picker beneath the raceway and extends in front of the picker stick. This lug may be of any suitable material and preferably of the same material as the picker and is shown as fitted in a slot in the picker and threaded over the rod 16. The face 29 of this lug opposite the picker stick and cooperating therewith is vertical and convex so that, notwithstanding the swinging movement of the picker stick, the picker stick engages this lug in the same horizontal plane.

A strap 30 is secured by screws 31 to the web of the picker and extends around its outer end and around the end of the picker

stick and around the lug 28 and is secured to the inner face of the lug by screws 32. Thus the upper end of the picker stick is loosely embraced and held in its proper relation to the picker and the lug 28.

Any suitable means may be provided for checking the movement of the picker stick. An ordinary type of picker check is shown at 33 secured to the lay and in addition a buffer in the form of a sinuous strap 34 threaded on the guiding rod 16 at its inner end is illustrated, also a buffer washer 35 at the outer end of the rod.

It will thus be seen that all the desired advantages are secured by this invention. The movement of the picker in a right line longitudinally of the lay and parallel with the raceway and the shuttle box walls is secured by the construction of, and guiding means for, the picker employed. The location and movement of the picker stick and its connection to the picker are such that there is no tendency to deflect the picker from this right line movement. The side walls of the shuttle box are left intact so far as the picker mechanism is concerned. Opportunity is afforded for the use of any desirable picker check and buffer. The construction is of a simple, rugged and efficient nature. The movement of the shuttle when picked from the box is therefore, so far as the picker mechanism is concerned, certain to be in a right line along the raceway and into the opposite box without deflection from its course.

Having thus described the invention, what is claimed as new, and desired to be secured by Letters Patent, is:

1. A loom comprising a lay having a raceway, a shuttle box on the lay at the end of the raceway, a picker extending above and below the raceway and mounted on the lay to slide longitudinally thereof with its head moving parallel to the raceway and midway of and parallel to the shuttle box walls, and a picker stick located entirely beneath the raceway and swinging in a plane parallel to and immediately adjacent to the picker and loosely connected at its upper end to the picker to impart longitudinal movement thereto.

2. A loom comprising a lay having a raceway, a shuttle box on the lay at the end of the raceway, a picker extending above and below the raceway and mounted on the lay to slide longitudinally thereof with its head moving parallel to the raceway and midway of and parallel to the shuttle box walls, a lug projecting laterally from the picker beneath the raceway and presenting a vertical convex face, a picker stick located entirely beneath the raceway and swinging in a plane parallel to the picker, means for loosely connecting the upper end of the picker stick to the picker opposite the convex face of the

lug to cause the picker stick acting against the lug to impart longitudinal movement to the picker.

3. A loom comprising a lay having a raceway, a shuttle box on the lay at the end of the raceway, a picker extending above and below the raceway and mounted on the lay to slide longitudinally thereof with its head moving parallel to the raceway and midway of and parallel to the shuttle box walls, a picker stick located entirely beneath the raceway and swinging in a plane parallel to the picker and immediately adjacent thereto, a lug projecting laterally from the picker in front of the upper end of the picker stick, and a strap extending from the picker around the upper end of the picker stick and acting loosely to connect the picker stick to the picker and maintain the picker stick in cooperative relation to the lug whereby the movement of the picker stick will impart longitudinal movement to the picker.

4. A loom comprising a lay having a raceway, a shuttle box on the lay at the end of the raceway, a picker extending above and below the raceway in a plane normal to the raceway and mounted on the lay to slide longitudinally thereof and guided in its sliding movement to maintain the shuttle engaging point of its head on a line parallel with the raceway, a picker stick located entirely beneath the raceway and swinging in a plane parallel to and immediately adjacent the picker and loosely connected at its upper end to the picker to impart longitudinal movement thereto.

5. A loom comprising a lay having a raceway, a shuttle box on the lay at the end of

the raceway, a picker extending above and below the raceway in a plane normal to the raceway and mounted on the lay to slide longitudinally thereof and guided in its sliding movement to maintain the shuttle engaging point of its head on a line parallel with the raceway, a picker stick located entirely beneath the raceway and swinging in a plane parallel to and immediately adjacent the picker and loosely connected at its upper end to the picker, and means for bodily moving the picker stick lengthwise during its swinging movement to cause its point of engagement with the picker to move parallel with the raceway, whereby there is no tendency on the part of the picker stick to impart anything other than longitudinal movement to the picker.

6. A loom comprising a lay having a raceway, a shuttle box on the lay at the end of the raceway, a longitudinal slot through the raceway at the shuttle box end, a rod secured to the lay and extending longitudinally thereof beneath and parallel with the said slot, a picker having a bore at its lower end fitting the rod, the said picker extending through and guided by the said slot whereby its head is accurately guided in its movement parallel with the raceway and longitudinally thereof, and a picker stick located entirely beneath the raceway and swinging in a plane parallel to and immediately adjacent the picker and loosely connected at its upper end to the picker to impart longitudinal movement thereto.

In testimony whereof, I have signed my name to this specification.

CARL D. BROWN.
